*B. Reiley,
Vapor Bath.
Patented Feb. 5, 1831.*

Boyle - Reilly X 0363

The defendant reported to the Hon. George Miller a small
ring part of the same containing a description in the
words of the said Boyle - Reilly himself of his new
Invention in apparatus for applying either simple
or medicated vapour, or steam, to the surface of the
Human body.

To all to whom these presents shall come. You are to know
that C. Boyle - Reilly of the City of Cincinnati in the
County of Hamilton and State of Ohio have invented
a new and useful improvement in apparatus for applying
either simple or medicated steam to the surface of the
Human body, with precision and safety in the
chamber of the neck, and that the following is a full and
exact description of the construction and operation
of said apparatus as invented and used by him.

Figure A. on drawing, represents the top or cover, which
should be made the points to that the wooden frame below
may be fitted perfectly tight to it, which, in using
Medicated vapour in a close room is indispensable, of
frame square or the ends is formed of four iron pipe
six inches and quarter an inch in width the frame to measure
five feet six inches in length and two feet one inch in
width, an opening is left at one end in the centre to admit
the neck of the patient, the ends of the iron at this opening
are connected by a circular piece of sheet iron which
covers the patients neck, the inner circle of which is low
sunk in the outer end of the iron substance as the iron
to which it is attached, one inch and a half is upper
and the end in a straight line off this circle of iron
is perpendicular to the plane of the neck of patient which
is connected, the circular plate must have a ring of
holes

holes around its centre, two inches apart and one and a half inches on the inside, to suit the flat-headed rivets desired. The circular plate is then attached to the frame with two rivets at each end, being on the outside of the frame and the ends of the circle kept one half inch from the lower edge of the frame which half inch goes into the groove of the wooden frame below. The proportion of which the arched ribs are formed, should be lighter than that of which the frame has been formed, the ribs should be five or more in number according to the strength of the iron used, the ribs at the head should be sixteen inches from the centre of the arch to the bottom of the frame, the rib at the foot ten inches, the intermediate ribs graduated by a straight line with the top, the other connected by a straight length of the iron running under the centre of the top with a rivet in each rib. The ribs are attached to the frame on the out sides within half an inch of the bottom line, with two rivets in each end, except the ribs to which handles are attached, one end of the handles being riveted in them for one of the rivets. The handles are made of iron wire three eighths of an inch in diameter, they are four inches in length and project one inch and a half, two of them are riveted in the straight centre piece of the top fifteen inches from each end. They are to enable one person to remove the top or cover, one of them is riveted at the lower end of the ribs at the head and foot, and the centre, they are for the purpose of forcing the frame into the wooden groove to which it will be fitted. The whole frame for the top or cover being thus formed is covered on the outside with strong padded leather, the ribs being covered around with strips of the same, and covered with the

the outside the cover laps around the lower edge of the frame and is sewed there and at the edges of the head and foot ribs where the covering of the top is joined to the sides with strong thread. The handles being let through the cover and the openings for the same carefully closed. Three coats of varnish laid warm on the inside is generally sufficient to close up the pores of the linen and prevent the escape of the vapors, and the action of the sulphur on the iron frame. It makes the varnish cut up two ounces of gum elastic into thin strips, put it into a quart of spirits of turpentine which will soon reduce it to a jelly, then to one gallon of linseed oil add one pound of litharge, one fourth of a pound each of sugar of lead, and white vitriol and one large onion stripped of its thin outer coats. Simmer the oil, onions and onion over a charcoal fire in a copper vessel capable of holding a much larger quantity, so that time may be afforded for removing the oil from the fire when there is danger of its boiling over. Stir the onions constantly from the bottom and when the onion assumes a dark brown color the oil may be removed from the fire having had time to settle, draw it off slow and add the gum and turpentine when it is ^{not} hot heat it by stirring with a brush, let each coat be well dried before another is added. The varnish being dry cover the bottom part of the frame all round with stout twotext cloth, neatly joined, so as to leave the frame ~~into which~~ it fits smooth and unbroken. The top may have an ornamental cover of oil cloth or other stuff, the handles covered with wood, binding or leather.

Figure B. on drawing represents the part of the apparatus on which the patient reclines. It consists of

two frames made of the inferior kind of Mahogany, or other wood combining lightness with strength. The inner frame is made to fit exactly within the outer or covered edge of the top or cover. The sides and ends are six inches wide or deep and three-fourths of an inch in thickness, dovetailed at the corners and rounded at the upper edges. Inside and out, a piece of stuff of the same breadth and thickness is dovetailed or webbed flush with each end of the bottom, and a piece three inches wide, across the centre of the same, two inches in width, to which the padding - re-clines - is attached, are secured to the inner sides with glue and four flat headed screws, countersunk on the outside. These legs run the whole length from head to foot, inclining from the top of the frame at the head, to the false or upper bottom at the foot. They are one inch and a quarter in width, and one inch in thickness. They have notches cut on the inside, one fourth of an inch in depth and three inches in length, which is the width of the webbing. The notches commence at two inches from the head, and continue at intervals of three inches to the inside or inside edge of the bottom board at the foot. The inside of the notches and the outer edges of the legs, are rounded smooth to save the webbing from wearing or cutting. The false or upper bottom board, of a hem, forms the papage by which the horse is supported. After having covered the points, two pieces of pine wood, two inches and a half in width at the foot, one inch at the head by one inch in thickness, resting on the bottom board on side are glued and nailed fast to the two pine boards at the foot, a piece of pine five inches and half a yard

and half an inch in thickness, and by bending its
length from side to side to fit into those pieces of wood,
one half inch from the inside of the head board, leaving
a passage of half an inch for the escape of the steam be-
tween the head board and bottom, four similar
pieces placed edge to edge each four inches wide &
extending from side to side and let in flush, extend
from the centre towards the head, to sustain the weight
of the patient when he sits down, previous to reclini-
ng; one piece of the same six inches in width let in
flush and extending between the webbing-lugs, joints
against the inside of the foot, as the admission pipe
from the furnace passes through this board and the
escape pipe is under it, so that it may be sometimes nes-
sary to open it, it should be fastened with screws in-
to the side pieces. The other pieces should be nailed fast
and being covered from the inside edge of the board at
the head to that of the foot with strong varnished linen
to the top. The false or upper bottom is thus formed,
and the steam is retained by covering the bottom of the
frame from head board to foot board in like man-
ner. The screws and nail heads inside the frame, should
be carefully covered with putty to preserve them from
the corroding influence of the steam, and the laths
which fasten the varnished linen on the upper bot-
tom may be secured by extening the edges of the linen
so as to cover over the lath heads, and fastened down
by introducing a little of the varnish between, —

The outer frame is built the workman will (of course)
fasten on before he applies the double covering of linen
to the bottom, as fitted exactly to the inner frame,
the sides and end pieces inches deep, three fourths of an
inch in thickness, and the sides by bending nine and

as past each end, to form the handles, the corners are mitred. The inside of the upper edge all round is rebated, so as to form a groove when attached to the inner frame half an inch depth, and wide enough to admit the cloth covered edge of the top or cover, fitting as close as possible, this groove may be slightly tapering towards the bottom, on the outer side, which has a tendency to keep the inside of the top frame against the rabbit formed by the difference ^{in depth} between the two frames which is one inch. Care must be taken to fit the top edge of the sides of one frame and the back edge of the other frame together, which has a tendency to keep the sides from springing, and thereby opening the groove in which the top is fitted and letting the vapor escape.

The appearance of the outer frame is much improved by rounding or swelling the sides and ends so as to leave a substance of one fourth of an inch on the outside of the pipe. The outer frame is carefully glued and secured by screws to the inner frame, the screw heads being countersunk on the inside of the inner frame and not coming partially through the outer frame. Four legs four inches long each are placed and glued into the lower edge of the rounded frames near to the ends, so that they may have the support of the laboratory, they are for the purpose of keeping the elbow of the tin pipes hereafter to be described, and also the bottom clear of the ground when the apparatus is set down; the legs of a sufficient height to apply the furnace and pipes to it, would be much in the way in taking it up, to the chambers, so it is calculated to be placed on four common chairs. A wooden rim must be made to go round the neck of the patient, the inner circle is ten inches in diameter, to correspond with the size of the head of the cover or top, it is one inch and a quarter square.

6363X

Feb. 5, 1831

and should be made of two thick pieces glued together, the grain of one crossing the other, the edge is deeply indented with a gauge well rounded, the inner edge is rounded off so as to be easy to the patient, this piece is attached to the iron ring at the head, after the cover is put on, by screws from the inside, the screw heads covered with the oil cloth, the ring cut off to suit the case will extend to the top of the gauge and be eight inches and a half from the top of the inner circle to the edge of the gauge when the top is in its place, the piece of the ring cut off being one inch and a half inside, is to fit into the head of the outer wooden frame, so as to form the upper part of the ring, and then glued fast, it will be necessary to reduce the thickness of this piece by being it even with the upper part, a piece of wooden cloth should be glued to the ends of the upper part to make the joint better if the outer frame is rounded it will be necessary to hollow out the end of the board under the curve to the depth of the round or swell.

Figure C on drawing represents the top of the wooden frame with the way in which the notches are applied covering both ends at the two upper notches, and after crooping them continue to cover them on the upper side all the way to the ends, where they are secured by eyelets holes and stout cord lacing, a piece of hard wood should be run into a loop or shank formed by lapping the ends of the webbing below the ends, the hole should admit the sleeve at the bottom may be covered by a movable piece of thin board prepared, it is however of little importance, as none but the feet of very tall persons can reach the aperture. Figure D. on drawing represents a circular

bottom, it rests on a wooden stand twelve inches high and about one inch in diameter, which holds in a piece of board twelve inches long, three inches wide and one inch thick, it is attached to the bottom board at the head by a lighter sheet of wood or sheath, from which it may be drawn and closed inside when the apparatus is covered, the which is raised or lowered to suit the convenience of the patient. Figure B an drawing represents a tin vessel four inches deep and three in diameter, three pieces of double tin should be riveted at equal distances round the rim to raise them half an inch on it about an inch. Three half gills of gunpowder with an equal quantity of water will burn about the time necessary for the patient to lie in the apparatus. Alcohol undiluted burns with too much violence. Figure D an drawing represents a tin vessel four inches deep and four inches diameter, it will be found large enough to contain water for simple steam, or sulphuric acid moderate vapour, if it is necessary to use larger, a larger vessel will be requisite.

Figure E an drawing represents a cap or cover twelve inches deep and eight inches diameter, made of strong tin, a handle riveted at the side, and a flange riveted to receive pipe H, which conducts the steam from the bottom of the apparatus, the vessels B & E are placed under this cap or cover, the bottom being open and the holes punched round the lower edge to admit of air. pipe H is one inch and half diameter and reaches the cap or cover E and the vessels B & E should be secured with rivets E, so as not to depend on solder, which is soon melted by the sulphur, the pipe I which receives the steam after it has passed over the patient

and returns between the bottoms to be conducted up the chimney) may be simply soldered, it is two inches diameter, an elbow for each of these pipes being made apart is secured to a plate of tin which is fastened in the center of the bottom board at the foot of the machine. The tin plate extending to the outer edge to prevent the heat from the furnace pipe $\frac{1}{2}$ incinerating the wood. This pipe must be conducted thro' both bottoms by a pipe flanged on the top so that it may not come in contact with the upper or lower bottom boards. The sides for its admission through which being at least two inches diameter, the lapping of the pipes at joints and elbows will of course be regulated by the course of the current of steam, the same as the pipe of a stove for smoke. To prevent the escape of the vapor thro' the opening of the head a band is made of strong silk coated on both sides with the gun varnish. This band (or bag open at both ends) must be long enough in circumference to pass over the wire at the head, it is twelve inches in length and covered on both sides with unvarnished silk or other thin material. The varnish feeling unpleasant to the patient should around one end is a drawing string, the string long enough to pass round the outside of the bag after it has been drawn tight round the wire. When using sulphur it cannot be made too secure. The patient should be divested of all his clothing unless he should wear a flannel dress next his skin. Should not that be the case, a loose flannel wrapper may be worn. The bag is put round the neck, the drawing string and next to the shoulders, the other end being laid in folds or folds round the neck, kept in these places by the grasp of the operator, a large silk handkerchief is passed

fold round, first under the edge, then above it, and drawn as tight as convenient to the patient when sulphur is used, it discolours the skin of the hand until the scalp skin peels off. This may be prevented if desired, by having covering for three of the four material as that of the neck, the penetrating action of the sulphur causes it to be painful to the patient, they should be covered by a bag made in like manner (This part of the preparation may be omitted with females.) the patient thus prepared should be seated on the frame between the centre and the head, reclining them on his side (which is the best position, if however the back is preferred the cushion for the head must be lowered down nearly to a level with the bottom or stocking) his hand resting on the cushion which should be elevated as high as convenient to him. The top is put on and carefully brought to its proper depth in the groove, the bag is now raised the sciss, as already explained, the alcohol ignited and the cap and pipe attached. Although I have made this application scores of times, being a proctane I require the patient to take medical advice in cases of difficulty in simple cutaneous or rheumatic cases, I pursue the following course. If the patient's skin is in any state I generally cause perspiration in a few minutes by steaming from half a pint of water placed over the alcohol in the tin reflect. perspiration appearing on the forehead is the proof, the head and cushion is again raised often deceiving the patient, the water being not used, a full half bunch of willow branches is put on the perfectly asperfed, which in the small application lasts as long to burn, as the patient can remain seated.

X6363

11

remain in it, the fire must be kept up fifteen minutes after the sulphur has burned out, to discharge the fume by the current of heated air, a strong ^{can} wind however remains, so that it will be necessary to raise the upper end of the top ^{shaving} made it (base all round) sufficiently high to let the patient out, it must then be replaced and the apparatus quickly removed from the apartment. In the recumbent position, the patient seldom feels farther relief previously reduced, should ^{such} symptoms appear the sulphur may be removed to the back of the fire place, the alcohol still kept burning in its place, the usual applications made to the patient such as admission of fresh air via gas, cool water &c. to the face, but the patient must remain in the apparatus, perhaps he will be as well as anywhere else till the fume is discharged, some of my medical friends have just informed me that carbon-phor has been lately used as a good substitute for the sulphur, in chronic cases. I feel convinced by much experience of the utility of outward applications, I have improvements, however, in store, & those capable of making them, hoping that my humble efforts will afford improved means for their use. The females have often been much terrified at being confined in an apparatus evidently communicating with the fire, I have planned a fire-bath which may be made connected to a bathing establishment or private dwelling, the principle the same, it may have the out ward appearance of a bed &c. the legs at the lower end or foot of the machine being hollow, the furnace may be placed in an adjoining room, the fume or steam conveyed in a pipe in

over a furnace, placed on the floor, from an apartment below, admitted through one leg, & discharged by the other. In a room without a fireplace, the portable apparatus may be used by having an additional elbow to the escape pipe, it can be put out of the window, the opening at each side filled up with a blanket &c, should a close stone be used, it may be introduced into it, in the absence of a fireplace or hearth however, some convenient conductor of heat should be placed between the furnace and the floor.
